(57) **CLAIM**

The ornamental design for a pair of brackets for a tool-less double curtain rod, as shown and described.

DESCRIPTION

FIG. 1 is a perspective view of the left bracket of a pair of brackets for a tool-less double curtain rod showing our new design, the pilot hole shown in broken lines forming no part of the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the right bracket of a pair of brackets for a tool-less double curtain rod showing our new design, the pilot hole shown in broken lines forming no part of the claimed design;

FIG. 9 is a front view thereof;

FIG. 10 is a rear side view thereof;

FIG. 11 is a left side view thereof;

FIG. 12 is a right side view thereof;

FIG. 13 is a top view thereof; and,

FIG. 14 is a bottom view thereof.
